UNITED STATES PATENT OFFICE.

ERNEST N. HUMPHREY, OF NEW BRITAIN, CONNECTICUT, ASSIGNOR TO UNITED ROYALTIES CORPORATION, OF NEW YORK, N. Y.

BEATER-BLADE SUPPORT.

Application filed May 6, 1926. Serial No. 107,216.

This invention relates to improvements in beater blade supports and it pertains particularly to improved means for attaching the upper ends of the wires to the lower end 5 of the supporting frame, the beater blades being journaled upon the said wire.

Heretofore much difficulty has arisen in attaching the upper ends of the wire on which the beater blades are journaled, to the 10 supporting frame, whereby the wire will not be twisted under strain, and during shipment. It is found that when these wires are twisted the beater blades are thrown out of line and the pinions carried by their upper 15 ends are thrown out of line which materially interferes with the proper operation of the machine. This has been known to be a difficulty in beaters and the like for many years, but a simple and effective manner of 20 attaching the ends of the wire to prevent them from possibly being twisted has not been heretofore devised.

The object of my present invention is to so construct the extremities of the wire that 25 they pass through the parallel portions of the supporting frame and attaching the wire to the supporting frame below its extremity, the two means serving to prevent the wires from any possible twisting in use or in ship- 30 ment.

A further object of my present invention is to form the vertical parallel sides of the lower end of the supporting frame with 35 openings, and the extremities of the wire with bent ends that pass through the said openings, and to weld, preferably by spot welding, the wires to the sides of the frame at points below their bent ends, whereby they are permanently attached to the frame, 40 making a rigid construction that is highly desirable in beaters of the type herein described.

A further object of my present invention is to form the vertical parallel sides of the 45 lower end of the supporting frame with openings, and the extremities of the wire with bent ends that pass through said openings, and to fasten the wires to the sides of the frame at points below their bent ends by 50 means of staples which penetrate the frame and are bent or crimped against the inner side of the frame to hold the wires rigidly in place.

A still further object of the invention is to form the vertical parallel sides of the lower 55 end of the supporting frame with openings, and the extremities of the wires with bent ends that pass through said opening, and to further form the frame with outwardly extending ears at the upper edge of the cut-out portion above the pinion gears, and to fasten the wires to the frame by crimping the frame ears over the wires.

Another and still further object of my 60 present invention is to provide openings adjacent the lower end of the supporting frame and to provide the extremities of the wires with inwardly bent ends which pass through 65 said openings, and to further provide the supporting frame at its lower ends with semi-circular shaped portions which surround and crimp the wires to the frame.

In the accompanying drawings, Figure 1 is a side elevation of the egg 70 beater showing the present improvement applied to the supporting wires.

Fig. 2 is an enlarged section through the lower end of the supporting frame, the manner of welding the wires to the frame being 75 shown.

Fig. 3 is a detached perspective view of the lower end of the supporting frame, the extremities of the wire being shown attached thereto by welding.

Fig. 4 is a side elevation showing the upper end of an egg beater having the agitator 80 blade supporting wires fastened to the beater supporting frame by welding the wires to the supporting frame from its inner side.

Fig. 5 is an enlarged detail perspective 85 view of the lower end of the supporting frame appearing in Fig. 4.

Fig. 6 is an enlarged sectional view taken on the line 6—6 of Fig. 5 looking in the direction indicated by arrow.

Fig. 7 is an enlarged detail view in side elevation of a modified form of attaching the wires to the supporting frame by the use of staples.

Fig. 8 is an enlarged transverse sectional 100 view taken on the line 8—8 of Fig. 7 looking in the direction indicated by the arrow.

Fig. 9 is an enlarged view in side elevation of a modified form showing the wires attached to the supporting frame by means 105 of ears.

Fig. 10 is an enlarged transverse sectional view taken on the line 10—10 of Fig. 9 looking in the direction indicated by the arrow.

Fig. 11 is a fragmentary view in side elevation showing a still further modified form of attaching the beater blade supporting wires to the beater supporting frame ends.

Fig. 12 is an enlarged view in side elevation of Fig. 11.

10 Fig. 13 is an enlarged transverse sectional view taken on the line 13—13 of Fig. 12 looking in the direction indicated by the arrow.

15 My present improvements are here shown applied to a beater having substantially parallel beater blades 1 and 2 supported on a wire 3 that is bent to substantially U-shape, the extremities of the wire 4 passing loosely through the upper ends of the beaters 5 and 20 passing loosely through the pinions 6.

In carrying forward my present improvement an ordinary form of supporting frame 7 is shown, the lower end of the supporting frame being bent substantially U-shape as 25 shown at 8, which forms vertical parallel portions 9 and end horizontal portions 10. Thus far we have explained the ordinary construction of a beater.

30 In carrying out my present improvement the parallel portions 9 of the U-shaped part 8 are provided with openings 11, and the ends 12 of the wire 3 extend upward beyond the pinions 6, the upper ends 13 of the ends 12 being bent laterally and passing 35 through the said openings.

40 This construction serves a triple function, in that when applying the wire 3 to the supporting frame 7 the laterally bent ends 13 serve to position the wires properly in respect to the frame so that the beaters 1 and 2 are always assembled in proper relation to correctly operate. Another object 45 of the laterally bent ends passing through the openings of the supporting frame is that their upper ends are held against lateral displacement and to some extent a twisting of the wires, and thirdly the wires are held in proper position so that they can be spot welded to the vertical portions 9 of the supporting frame.

50 The wires, having their ends placed in the said openings and the blades being assembled on the wires with their pinions 6, a spot weld is made between the ends 12 and the parallel portion 9 at a point between the pinions and the laterally turned ends 13. Preferably the spot weld is made at about the points 14. In making a spot weld, the metal, as well understood, is somewhat distorted since it is brought to a welding heat and then pressed by the welder and the current cut off when the weld is completed. The weld is quickly made, and is together with the laterally bent ends of the wires effective in holding them rigidly in their posi-

tion against either twisting or any displacement whatever.

While I show the wires 12 located at the outer sides of the parts 9 of the supporting frame, I desire it to be understood that the 70 wires may be placed at the inner sides of the parts 9 of the supporting frame, in which event the ends 13 will be turned outward instead of inward, and in that event the weld is made in substantially the same 75 manner as when the wires are outside. The reversal of the wires will be readily understood so that it is unnecessary to show them in the reversed positions.

I desire it understood that changes may 80 be made in the present improvement without departing from the scope of the invention, so long as the change is within the scope of the appended claims.

Some of the changes which might be readily made in the present invention are set forth in Figs. 4 to 13 inclusive, the detailed description of which follows hereinafter.

Referring to Figures 4 to 6 inclusive, particularly, which show a modified form of 90 attaching the beater blade supporting wires to the beater blade supporting frame, it will be seen that there is here utilized the same supporting frame 7 having a U-shaped portion, the vertical walls of the U being designated by the numeral 9. There is also utilized the same beater blade supporting wire 3, the upper extremities of which are designated by the numeral 4. The vertical walls 9 of the supporting frame are provided with 95 openings which receive inturned ends 13 of the supporting wires. Below these openings the walls 9 are provided with vertical grooves or channels 15 which receive the upper extremities of the wires 3 and aid in 100 preventing lateral displacement of them. To circumvent any possibility of displacement in any direction, the wires are spot 105 welded as at 16 and thus rigidly held in the channels or grooves 15. This weld is made 110 in the inner side of the walls 9, or more accurately, from the inner sides of the channels 15.

Referring to Figures 7 and 8, there appears a still further modification of the manner of attaching the beater blade supporting wires to the beater support.

115 In these figures of the drawings, the support is designated by the numeral 7 and is provided with a U-shaped lower end having vertical side walls 9 and horizontal bottom portion 10. The beater blade supporting wires have upwardly extending extremities 4 which parallel the outer faces of the vertical walls 9 being seated in grooves or 120 channels 15 provided therein. The extreme upper ends of the supporting wires are inturned and pass through the openings 11 to the inner side of these vertical walls.

125 It will be readily understood that the 130

channels or grooves 15, tend to hold the supporting wires against lateral displacement but to assure that the wires are firmly held against displacement in any direction

5 they are provided with staples 17 which have their inner ends passing through the vertical walls 9 of the supporting frame and crimped or clamped outwardly against the inner face of said walls, as clearly appears
10 at 18.

In a construction of this character the supporting wires are locked against displacement and accordingly firmly clamped to the supporting frame.

15 Referring to Figures 9 and 10 of the drawings, it will be seen that there appears a still further modification in the manner of attaching the supporting wires to the U-shaped supporting frame.

20 In these figures of the drawings the supporting frame is again designated by the numeral 7 and its vertical lower ends by the numeral 9, and its horizontal bottom portion by the numeral 10. This frame is likewise provided with the channels or 25 grooves 15 for receiving and guarding the upper ends 4 of the supporting wires from lateral displacement. The supporting ends of these supporting wires are bent inwardly 30 as at 19 to pass through the openings 11 provided in the supporting frame side walls at the upper end of the channels 15.

Adjacent the lower ends of the channels 15 and at opposite sides thereof the supporting frame vertical walls 9 are provided with outwardly extending horizontal ears 20 adapted to receive between them the supporting wires 3. To definitely and firmly clamp the supporting wires in place in the 40 supporting frame channels these ears are bent towards one another, as clearly appears in dotted lines at 21 in Figure 10 of the drawings. It will be seen that these ears when bent, definitely engage and crimp over the supporting wires, thus securing 45 them against displacement.

In Figures 11 to 13 inclusive, there appears a still further modified form of attaching the beater blade supporting wires to the beater blade supports.

50 In this instance the beater blade support is of a slightly different construction, comprising two vertical members 22 and 23 in parallel spaced relation and supporting between them the driving gear wheel 24 carrying the operating handle 25. Adjacent their lower ends the beater supporting arms 22 and 23 are bent outwardly as at 26 while their lower ends terminate in elongated outwardly extending ears 27 below which are mounted the beater blades 28 superimposed by the pinion gears 29.

The beater blade supporting wires are similar to those heretofore described and 55 provided with upwardly extending ends 4

the extremities of which are bent inwardly to pass through suitable openings 11 in the arms 22 and 23 so that their inner ends penetrate these arms as clearly appears at 13. When the supporting wires have been positioned so that their inturned ends are extending through the openings 11, the outwardly extending ears 27 are bent over and clamped firmly down upon the upper ends 4 of the wires as clearly appears at 30, each 75 ear assuming a semi-circular form and guarding the wires against displacement and any possible chance of detachment from the supporting arms 22 and 23.

70 From the foregoing description it will be seen that I have provided a cheap yet efficient manner of attaching the agitator supporting wires to the beater supporting frame and one which is simple of manufacture.

Having thus described my invention what 80 I claim and desire to secure by Letters Patent is:

1. A beater comprising a supporting frame, an agitator, and an agitator supporting wire, said frame provided with outwardly extending ears adjacent its lower end, and said ears crimped inwardly over the wire to fasten the same to the frame.

2. A beater comprising a supporting frame, an agitator, and an agitator supporting wire, said frame provided with longitudinal grooves having adjacent their lower ends outwardly extending ears, and said wire fastened in said grooves by crimping the frame ears inwardly over the wire.

95 3. A beater comprising a supporting frame, an agitator, and an agitator supporting wire, said frame having vertical portions provided with vertical grooves terminating in openings at their upper ends and provided with outwardly extending ears adjacent their lower ends, the supporting wire positioned between said ears in said channels and having its ends bent laterally to 100 pass through said openings, and the wire fastened in said position by crimping the ears over and downwardly upon the wire.

105 4. A beater comprising a supporting frame, an agitator, and an agitator supporting wire, said frame provided with vertical portions in separated parallel relation having therein vertical grooves terminating in their upper ends in openings and provided adjacent their lower ends with outwardly extending ears in separated relation, the supporting wire ends positioned between said ears and lying in said grooves with the upper extremities of the wire bent laterally to pass inwardly through said openings, and said wires fastened in position by crimping the ears over and downwardly upon the wire.

115 5. A beater comprising a supporting frame, an agitator, and an agitator supporting wire, the lower end of said frame pro-

vided with outwardly extending vertically elongated portions, said wire passing between said frame and elongated portions and fastened to the frame by crimping the elongated portions over the wire.

6. A beater comprising a supporting frame, an agitator, and an agitator supporting wire, the lower ends of said frame bent outwardly, the frame provided with openings above said outwardly bent portions, the supporting wire positioned between said outwardly extending frame portions and having its upper extremities bent to pass through said openings, and the supporting wire fastened to the frame by bending said outwardly extending portions over the wires to form semi-circular bearings.

7. A beater comprising a supporting frame having its lower end substantially U-shaped, beaters, a supporting wire substantially U-shaped and having its parallel portions passing through the beaters, the upper ends extending beyond said beaters, the parallel portions of the supporting frame having horizontal openings located above their lower ends, the upper ends of the supporting wire located outside of said parallel

portions of the frame, and having their upper ends projecting inwardly in opposite directions through the said openings, and connecting means located below the turned in ends of the wire and above the lower ends of said parallel portions of the frame for securing the upper ends of the rod to the said frame.

8. A beater comprising a frame having its lower end U-shaped, beaters below the said U-shaped end, a U-shaped supporting wire supporting said beaters, the parallel portion of the supporting frame having the horizontal openings above the lower end of the frame, the upper ends of the supporting frame extending along the parallel portions and its extremities bent in opposite directions and passing through the said openings, and means connecting the upper ends of the wire to the parallel portions, said means located between the bent ends of the rods and the lower end of the U-shaped frame.

In testimony whereof I hereunto affix my signature.

ERNEST N. HUMPHREY.
